ABSTRACT: In underwater dredging, the ambient pressure in the soil or sand being dredged adjacent the tip of the dredging pipe which is buried in the sand is used to control the dredging machinery so that the output of dredged material is increased. A pressure sensitive device is used to anticipate variations in concentration of the sand in the suspension of sand in water being dredged.

MECHANISM FOR ANTICIPATING THE
CONCENTRATION OF SAND IN A DREDGING
SUSPENSION

The invention relates to a suction dredger installation, comprising a suction pipe connected to a pump. A known suction dredger installation of the kind specified is used in many cases for sucking up dredger spoil, the end of the suction pipe being inserted in the soil. The suction process is then influenced by the particular varying circumstances present adjacent the end of the suction pipe. The output which can be obtained with the prior art suction dredger installation depends considerably on the technical skill and experience of the dredging supervisor in groping in the dark.

The invention provides an improved suction dredger installation which is characterized by at least one pressure-sensitive element which senses the pressure in the soil adjacent the end of the suction pipe.

A larger output can be obtained with the improved suction dredger installation according to the invention if the pressure in the soil adjacent the end of the suction pipe is known. This is an important indication which is not available with the prior art suction dredger installation. Hitherto, for regulating the suction process, a quantity to be regulated e.g., the conveyed concentration of dredger spoil in the suspension sucked up, has been regulated by measuring this quantity, or a quantity dependent thereon, in the suction pipe and correcting this quantity in dependence on the difference between the measured and required values, whereas the suction dredger installation according to the invention enables the future value of the quantity to be regulated to be predicted by taking into account the pressure in the soil adjacent the end of the suction pipe, thus also enabling this particular quantity to be regulated in anticipation, in dependence on the pressure in the soil.

In a further development of the suction dredger installation according to the invention, at least one regulating member for regulating the suction process is acted upon by the sensed value emanating from the first-mentioned pressure-sensitive element.

Preferably, the pressure-sensing element forms part of a depth-measuring system for measuring the depth at which the end of the suction pipe is situated below the surface of the soil.

If it is known at what depth the end of the suction pipe is situated in the dredger spoil, the suction pipe can be duly displaced, or duly inserted more deeply into the soil, to prevent clay and other impurities floating on the sand from being sucked up instead of sand. When the top layer of the soil is being sucked up there is a considerable risk that the suction mouth may be clogged by large objects which are often to be found on the surface of the soil. Stagnation caused by clogging of this kind can be substantially obviated by using the suction dredger installation according to the invention.

Preferably, the suction dredger installation according to the invention is so constructed that the depth-measuring system comprises a pressure-difference pickup, one side of which is acted upon by the first-mentioned pressure-sensing element disposed adjacent the end of the suction pipe, the other side being acted upon by a second pressure-sensitive element which senses the water pressure above the soil.

These and other features of the invention will be clearly gathered from the following description of a number of embodiments of a suction dredger installation according to the invention, with reference to the diagrammatic drawings, wherein:

FIG. 1 is a drawing illustrating a suction dredger installation according to the invention during the sucking up of sand and

FIG. 2, 3 and 4 each shew the lower end of the suction pipe of variant embodiments of the suction dredger installation according to the invention.

The suction dredger installation according to the invention shown in FIG. 1 comprises a ship 10, a pump 11, a pressure line 12 connected to the pressure side of the pump 11, and a

suction pipe 13 which has a suction mouth 20 and is connected to the suction side of the pump 11. In the embodiment illustrated, the pump 11 is disposed at the level of the water 14, and the suction pipe 13 can pivot around the center line of the pump 11.

FIG. 1 shows (counting upwards) a layer of sand 15, a layer of clay 16, and water 18. The free end of the suction pipe 13 is inserted into the soil, to a great depth, for instance 20 m. The soil shown enclosed by a chaindot line 19 and surrounding the end of the suction pipe 13 is brought into suspension by under-digging. Outside the line 19, the soil is in its normal undisturbed condition.

If during the sucking up of sand, the quantity of sand brought into suspension which is still above the suction mouth 20 is known, this quantity can be taken into account during the sucking up of sand and the displacement of the suction pipe 13.

To this end, the suction dredger installation shown in FIG. 1 has a measuring system mainly consisting of a pressure pickup 21 at the end of the suction pipe 13 and an indicator 22. The pressure pickup 21 measures, by means of a pressure-sensitive element forming part of the pressure pickup 21 and not shown in detail, the local prevailing pressure produced by a column of sand H_3 , a column of clay H_2 and a column of water H_1 .

The indicator 22 consists of a pointer 23 which is attached to the suction pipe 13 and has a graduated scale 24 from which the angle α can be read off, which the suction pipe 13 encloses with the horizontal plane.

The depth H of the pressure pickup 21 below the surface 14 of the water is equal to $k \sin \alpha$, where k is the length of the suction pipe from the surface 14 of the water to the pressure pickup 21. The height H_3 of the column of sand can now be calculated by the equation:

$$P = H_1 + S_k \cdot H_2 + S_s \cdot H_3$$

Where:

P is the pressure measured by the pressure pickup 21,

H_1 is the water column

S_k is the specific weight of the clay

H_2 is the column of clay

and S_s is the specific weight of the sand.

$$H_1 = H - H_2 - H_3 \operatorname{axksin} \alpha - H_2 - H_3$$

From the two above equations there follows:

$$H_3 = \frac{P - k \sin \alpha - (S_k - 1)H_2}{S_s - 1}$$

The column of clay H_2 , and the specific weight S_k are measured by carrying out drillings. The specific weight S_k of the drifting sand is a value known for a particular kind of sand, for instance, 1.8 kg./dm³.

The column of sand H_3 can be measured considerably more simply and accurately by means of a known pressure-difference pickup 25 which is used in the suction pipe 45 illustrated in FIG. 2; in the pressure-difference pickup 25 one pressure chamber 28 is acted upon by the local pressure in the soil the other pressure chamber 26 being connected via a line 27 to the water 18 above the soil. In this case the relative pressure pickup 25 measures a pressure

$$P_r = 1 \cdot H_1 + S_k \cdot H_2 + S_s \cdot H_3 - 1 \cdot H$$

Then we have $H_3 = \frac{P_r - H_2 \cdot S_k + H_2}{S_s - 1}$

The pressure chamber 28 is separated from the soil by a diaphragm 17. Thus the measuring diaphragm 47 is protected from damage. The diaphragm 17 forms a first pressure-sensing element which is directly acted upon by the pressure in the soil and transmits this pressure via the liquid in the chamber 28 to the measuring diaphragm 47, while the inlet aperture 46 of the line 27 forms the second pressure-sensing element, from which the sensed pressure is transmitted via the liquid in the line 27 and in the chamber 26 to the measuring diaphragm 47.

The suction pipe 38 shown in FIG. 3 has a measuring system formed by a pressure water line 29 which is connected to a pressure source and branches into two narrow branches 30, 31 which have respectively a first outflow aperture 32 in the soil adjacent the suction mouth 34, thus forming a first pressure-sensing element, and an outflow aperture 33 which discharges above the soil into the water 18, thus forming a second pressure-sensitive element. Adjacent the outflow apertures 32, 33 the branches 30, 31 are connected to either side of the pressure-difference pickup 37 via measuring lines 35 and 36 respectively. The pressure-difference pickup 37 thus measures the difference in pressure between the apertures 32 and 33. The column of sand H_3 above the outflow aperture 32 can be derived therefrom.

The suction pipe 38 shown in FIG. 3 comprises a pipe 39 which is connected to the pump 11, and a telescopic pipe 40 which can be moved axially in the pipe 39 by a hydraulic ram 41. Disposed around the pipe 39 and the telescopic pipe 40, is an external jacket 42 which is attached to the pipe 39 and whose upper side is open and in communication with the water 18. The suction mouth 34 in which a heavy suspension of a large quantity of sand with a little water enters, is disposed at the lower end of the outer jacket 42. In proportion as the telescopic pipe 40 is drawn further upwards, a larger quantity of water comes into the telescopic pipe 40 via the outer jacket 42 along the lower edge 43 of the telescopic pipe 40, and is also sucked up. On the other hand, the sand rises higher in the outer jacket 42 in proportion as the jacket 42 is inserted more deeply into the soil. The concentration of sand in the suckedup suspension can now be regulated by adjusting the distance of the edge 43 above the suction mouth 34 in dependence on the depth thereof in the soil, or in other words in dependence on the pressure measured by the relative pressure pickup 37.

The measuring system is very useful for regulating the concentration of dredger spoil in the suckedup suspension.

The aperture 32, and the pressure pickups 21 and 25 are preferably not disposed in exactly the same place as the suction mouth, but at a small distance m thereabove, where the flows around the suction mouth have little effect on the pressure measured, if any. When determining the depth of the suction mouth, the depth of the pressure pickup is then added with $m \sin a$.

The pressure pickup 21 and the relative pressure pickups 25 and 37 are, for instance, of the known electric type and are each connected via electric wires to an indicating system (not shown) disposed on the control panel on board of the ship.

The members of the suction pipe 138 shown in FIG. 4 corresponding with members of the suction pipe 38, have like reference numbers that are 100 higher however.

The suction pipe 138 has a measuring system formed by a pressure water line 129 which is connected to a water source and has an outflow aperture 132 in the soil adjacent the suction mouth 134, the outflow aperture 132 forming a pressure-sensitive element connected via a measuring line 135 to a pressure pickup 137 whose diaphragm 144 picks up the pressure sensed in the soil. The electric output signal from the pressure pickup 137 is fed via a line 148 to a measuring member 149 which operates a hydraulic regulating valve 150. This regulating valve 150 controls a hydraulic ram 141 for adjusting the height of telescopic pipe 140.

The output signal from the pressure pickup 137 can also be controlled by other regulating members (not shown) for regulating the suction process, for instance, the governor (not shown) of the pump motor. Moreover, as well as being adjusted in dependence on the pressure in the soil sensed by the pressure-sensitive element, the height of the telescopic pipe 140 in relation to the suction mouth 134 can be adjusted in dependence on other measured values (not indicated in detail).

What we claim is:

1. A suction dredger assembly of the type including a fluid pump having a suction inlet and a pressure outlet, and dredging conduit means having one end connected to said suction inlet and having an opposite end inserted below the bottom of a body of water into a region of material desired to be dredged so as to deliver a suspension of said material in water at said outlet of the pump, the improvement of which comprises,

30 pressure sensing means supported on said opposite end of the conduit means for producing an output signal proportional to the pressure in said material outside said opposite end of the conduit means whereby the depth at which said opposite end of the conduit means is situated in said material may be determined; and

35 control means for controlling said dredger assembly to maximize the output of said material delivered by said pump in accordance with the pressure sensed by said pressure sensing means.

2. The assembly as defined in claim 1, wherein said conduit 40 means comprises an outer pipe defining, at its lower extremity, said opposite end of the conduit means, and having its upper extremity above the level of said bottom and within said body of water, an inner pipe connected at its upper end to said suction inlet and having a lower end portion presenting a lower 45 extremity disposed within the confines of said outer pipe; said control means being connected to said lower end portion of said inner pipe for varying the spacing between the lower extremity of said inner pipe with respect to the lower extremity of said outer pipe.
